UNITED STATES PATENT OFFICE.

ARTHUR BENNETT, OF HOLLINWOOD, ENGLAND.

MACHINE FOR SPLICING AND PIECING UP COTTON, LINEN, OR SIMILAR THREADS.

1,396,618.

Specification of Letters Patent.

Patented Nov. 8, 1921.

Application filed April 2, 1921. Serial No. 458,168.

(GRANTED UNDER THE PROVISIONS OF THE ACT OF MARCH 3, 1921, 41 STAT. L., 1313.)

To all whom it may concern:

Be it known that I, ARTHUR BENNETT, a British subject, residing at Hollinwood, Lancashire, England, have invented certain new and useful Improvements in Machines for Splicing and Piecing up Cotton, Linen, or Similar Threads, for which I have filed application in Great Britain No. 20,529, dated September 11, 1913, Patent No. 20,529, dated September 11, 1913, of which the following is a specification.

This invention relates to improvements in machines for splicing and piecing up cotton, linen or similar threads.

It consists essentially of a machine which will automatically take out the twist in the two ends to be spliced together, and after splicing re-insert the twist into the spliced thread, and in which the spindles are arranged in two parallel rows so that the thread from any number of pairs of bobbins can be spliced together at one operation.

The invention will be fully described with reference to the accompanying drawings:—

Figure 1 is a front view of the driving end of the machine.

Fig. 2 is a plan of the machine.

Fig. 3 is a transverse section.

Fig. 4 is a perspective view of the knocking off motion.

Fig. 5 is a perspective view showing the mechanism for holding the threads while the twist is being taken out and re-inserted.

The frame A of the machine is of any suitable construction and is provided along the front with a fixed rail B carrying a number of spindles b to carry bobbins E and at the rear with two or more rails C C' mounted one above the other in a suitable frame D. The frame D is controlled by a rack d and pinion d' mounted on shaft d² to bring any of the rails C C' into operative position, the shaft d² being rotated by a hand wheel at the end thereof. The rails C C' are provided with spindles c c' to carry bobbins E', the spindles c c' on the rails C C' being equal in number and opposite to the spindles b on the fixed rail E.

At one end of frame A a shaft f is mounted carrying a fast and loose pulley F driven by hand or from any suitable source of

power. Two pulleys G G' are keyed to the shaft f, one at each end of the fast and loose pulley F. The pulley G² is connected by a crossed belt g with a fast and loose pulley H mounted on a shaft J running the length of the frame A and the pulley G' is connected by an open belt g' with a fast and loose pulley H' also mounted on the shaft J.

The crossed belt g is controlled by a belt fork h sliding on a rod h² and the open belt g' is controlled by a belt fork h' also sliding on the rod h². The belt fork h is provided with a downwardly projecting arm h³ carrying a rod h⁴ sliding through a frame K. The rod h⁴ carries a spring k held between an abutment stop k' on the rod h⁴ and the frame K. The spring k holds the belt g on the loose pulley and when the fork h is moved to put the belt g on to the fast pulley the spring is compressed. The abutment stop k' carries a bar k² provided with a notch k³ into which a weighted lever k⁴ falls when the belt fork h is moved to bring the belt g into position on the fast pulley, thus preventing the spring k from moving the fork h back again until the lever k⁴ is raised by an automatic knock-off motion which will be described later.

The belt fork h' controlling the movement of the open belt g' is provided with an upwardly projecting arm h⁵ carrying a rod h⁶ also sliding through the frame K. The rod h⁶ carries a spring h⁵ held between an abutment stop h⁶ on the rod h⁶ and the frame K. The spring h⁵ holds the belt fork h' in the position to maintain the belt g' on the loose pulley and when the fork h' is moved to put the belt g' on to the fast pulley the spring h⁵ is compressed. The abutment stop h⁶ carries a bar h⁷ provided with a notch h⁸ into which a weighted lever h⁹ falls when the belt fork h' is moved to bring the belt g' into position on the fast pulley, thus preventing the spring h⁵ from moving the belt fork h' back again until the lever h⁹ is raised by the automatic stop motion which will be described later.

The bosses of the belt forks h and h' are made sufficiently wide so that when one is in the position to bring the corresponding belt

on to its fast pulley, the other cannot be moved. In Figs. 1 and 2, both belts are shown on the loose pulleys, the loose pulleys of each fast and loose pulley H or H' being on the outside and the fast pulley on the inside.

The shaft J is the shaft which operates the mechanism for first taking the twist out of the ends of yarn or thread to be spliced and then after splicing reinserting 10 the twist therein so that it is necessary that the shaft J should be first rotated in one direction for a predetermined number of revolutions and then after the ends of the 15 yarn or thread have been spliced together, rotated in the opposite direction for an equal number of revolutions.

The predetermined number of revolutions which the shaft J has to make depends on the amount of twist in the ends of the 20 yarn or thread being spliced together.

The fast pulley of the fast and loose pulley is employed to rotate the shaft J in the direction for removing the twist from the ends to be spliced together and the fast 25 pulley of the fast and loose pulley H' is employed to rotate the shaft J in the opposite direction to reinsert the twist after splicing. The functions of the pulleys H and H' could be reversed depending on the 30 direction of rotation of the main driving pulley F.

In order to insure that the right amount of twist is taken out of the ends before 35 splicing and that the same amount is reinserted after splicing, it is necessary to provide an automatic knock off motion which will release the weighted lever k⁴ from the notch k³ in the rod k² and allow the spring k to return the belt fork h to the 40 loose pulley of the fast and loose pulley H to stop the rotation of the shaft J when the requisite amount of twist has been taken out of the ends and which will also release the weighted lever k⁹ from the notch k⁸ in 45 the bar k⁷ to permit the spring k⁵ to return the belt fork h' to the loose pulley of the fast and loose pulley H' to stop the rotation of the shaft J when the same amount of twist has been re-inserted into the ends 50 after they have been spliced together.

This automatic knock off motion comprises a vertical rack L in a slot in which are inserted two projecting T headed pins M M' which can be held in any desired 55 position by means of the clamping nuts m m'. The end of the pivoted weighted lever k⁴ holding the belt fork h with the belt g on its fast pulley is arranged in the path of the lower pin M and the end of the pivoted 60 weighted lever k⁹ holding the belt fork h' with the belt g' on its fast pulley, is arranged in the path of the upper pin M'. It will thus be seen that when the rack L has moved downward until the pin M has 65 engaged the lever k⁴ the latter will be moved

out of engagement with the notch in the rod k² and the spring k will move the belt fork h and cause the latter to carry with it the belt g from the fast to the loose pulley and so stop the rotation of the shaft J. Similarly when the shaft J is being rotated in the opposite direction by the belt g' to reinsert the twist the engagement of the pin M' with the end of the pivoted weighted lever k⁹ will cause the latter to be moved 70 out of engagement with the notch in the rod k⁷ and the spring k⁵ will move the belt fork h' to carry the belt g' from the fast to the loose pulley thus stopping the rotation of the shaft J. 75

The rack L is carried in a suitable supporting tube L' which is graduated to correspond to the number of revolutions of the shaft J required to take out and insert any given twist and is provided with a pointer l 80 working over the graduations to assist in the adjustment of the pins M and M'.

The rack L is operated from a small pinion l' on the shaft J which gears with a larger toothed wheel l². The wheel l² is 90 connected to the small pinion l³ which gears with the large wheel l⁴ keyed to a stud on a shaft on which is also keyed the pinion l⁵ gearing with the teeth l⁶ of the rack L. The rack L carrying the knocking off pins 95 M M' is thus connected to the shaft J and comes into operation as described above.

The shaft J running the whole length of the frame A carries a number of pairs of spiral gears j j', the number of pairs of 100 such gears being equal to the number of spindles b carried on the front fixed rail B. The spiral gears j j' gear with spiral gears n n' mounted on shafts n² n³ on the ends of which are carried the yarn clamping devices N N'. The clamping devices N N' as will be seen from Fig. 5 are in the form of a screw the yarn being held between the head thereof and the flattened end of the shaft. The spiral gears n and shafts n² 110 of the clamping devices N for the thread or yarn from the bobbins E are provided with slits extending to the center to receive the thread or yarn but such an arrangement is not necessary for the thread or yarn from 115 the bobbins E' as in this case the thread does not extend beyond the clamp.

The other ends of the yarn or thread are held by clamping devices O adjacent to the bobbins E'. The clamps O comprise a fixed 120 plate o mounted on a bar P and a plate o' carried on a rod O' screwed at the end o² engaging in the nut o³. To clamp or unclamp the yarn or thread it is only necessary to rotate the rod o' when all the ends 125 in the frame are clamped or unclamped together. The bar P is mounted on wedges p and held by winged nuts p' so that if the latter are slackened the wedges p can be driven in to tilt the bar P and slacken 130

the yarn or thread held between the clamps N and O.

A bar Q is arranged between the bevels *n* and the bobbins E provided with pins *q* engaging the yarn or thread. The bar Q is connected by a cord *q'* passing over a pulley to a weight to impart a certain amount of drag to the yarn or thread.

Where a thread is composed of a number 10 of strands it is advantageous to break the ends of the strands at different points along the length thereof to obtain a more uniform splicing. To obtain this a framework R is provided between the clamps N and O. 15 (See Fig. 5.) The frame R is composed of a number of strips *r* carrying cutting edges *r'* so that the different strands can be severed as desired.

In operation the bobbins to be spliced together are placed on the spindles *b* and *c* (or *c'*) and the ends held between the clamps N and O as shown in Fig. 2. The shaft J is then rotated the necessary amount to take the twist out of the length between 25 the points N and O, the shaft J being stopped by the automatic knock off when this has been done. One of the ends is then removed from its clamp and laid over the other end and then spliced together. The 30 shaft J is then rotated in the opposite direction to re-insert the twist the automatic knock off motion stopping the rotation of the shaft J, when this has been completed. The bobbins are then removed from the 35 frame.

What I claim as my invention and desire to protect by Letters Patent is:—

1. A machine for splicing or piecing up cotton, linen or similar threads comprising 40 clamps for the ends of the threads, a shaft rotating said clamps first in one direction and then in the other to take out and re-insert the twist in the ends, fast and loose pulleys driving said shaft, first in one direction and 45 then in the other, and an automatic knock-off motion to stop the rotation of the shaft after making the predetermined number of revolutions for taking out or re-inserting the twist.

50 2. A machine for splicing or piecing up cotton, linen or similar threads comprising a stationary rail at the front of the machine, spindles for bobbins mounted thereon, a plurality of rails at the rear of the machine 55 capable of being moved up and down vertically, spindles for bobbins mounted thereon, stationary clamps mounted on a bar in front of the movable rails, revolving clamps adjacent to the stationary rail, a 60 shaft rotating the said revolving clamps first in one direction and then in the other, gearing connecting the shaft to the revolving clamps, a pair of fast and loose pulleys mounted on the shaft and an adjustable 65 automatic knock off motion to stop the rota-

tion of the shaft after it has made a predetermined number of revolutions in either direction.

3. A machine for splicing or piecing up cotton, linen or similar threads comprising 70 a stationary rail at the front of the machine, spindles for bobbins mounted thereon, a plurality of rails at the rear of the machine capable of being moved up and down vertically, spindles for bobbins mounted thereon, 75 a bar in front of the movable rails, carrying a number of plates affixed thereto, an equal number of plates pressed against the former plates to grip the yarn or thread, a number of short shafts arranged adjacent to the 80 fixed rail, screw clamps at the ends of said shafts to grip the yarn or thread, a shaft rotating the short shafts, first in one direction and then in the other, gearing connecting the shaft to the revolving clamps, a 85 pair of fast and loose pulleys, mounted on the shaft and an adjustable automatic knock off motion to stop the rotation of the shaft after it has made a predetermined number of revolutions in either direction. 90

4. A machine for splicing or piecing up cotton, linen or similar threads comprising a stationary rail at the front of the machine, spindles for bobbins mounted thereon, a plurality of rails at the rear of the machine 95 capable of being moved up and down vertically, spindles for bobbins mounted thereon, a bar in front of the movable rails carrying a number of plates affixed thereto, an equal number of plates pressed against 100 the former plates to grip the yarn or thread, a number of short shafts arranged adjacent to the fixed rail, screw clamps at the ends of said shafts to grip the yarn or thread, a shaft rotating the short shafts first in one 105 direction and then in the other, gearing connecting the shaft to the short shafts, a pair of fast and loose pulleys mounted on said shaft, belt forks controlling the belts on 110 said pulleys, spring controlled bars normally holding the belt forks on the loose pulleys, weighted levers to engage projections from said bar to hold the springs out of action, a rack driven from the rotating shaft and pins on said rack to release the 115 weighted levers from engagement with the projections on the bars to allow the belt forks to return to the loose pulleys, and stop the rotation of the shaft.

5. A machine for splicing or piecing up 120 cotton, linen or similar threads comprising a stationary rail at the front of the machine, spindles for bobbins mounted thereon, a plurality of rails at the rear of the machine capable of being moved up and down vertically, spindles for bobbins mounted thereon, a bar in front of the movable rails carrying 125 a number of plates affixed thereto, an equal number of plates pressed against the former plates to grip the yarn or thread, a 130

number of short shafts arranged adjacent to the fixed rail, screw clamps at the ends of said shafts to grip the yarn or thread, a shaft rotating the short shafts, first in one direction and then in the other, gearing connecting the shaft to the short shafts, a pair of fast and loose pulleys mounted on said shaft, belt forks controlling the belts on said pulleys, spring controlled bars normally holding the belt forks on the loose pulleys, weighted levers to engage projections from said bar to hold the springs out of action, a rack driven from the rotating shaft, pins on said rack to release the

weighted levers from engagement with the projections on the bars to allow the belt forks to return to the loose pulleys and stop the rotation of the shaft, and a frame placed between the clamping devices carrying knives to sever the strands of the thread at different points.

In testimony whereof I have hereunto set my hand in presence of two subscribing witnesses.

ARTHUR BENNETT.
